RAILWAY CAR DIAPHRAGM
CONSTRUCTION

Martin P. Blomberg, Hinsdale, Ill., assignor to
General Motors Corporation, Detroit, Mich., a
corporation of Delaware

Application August 2, 1940, Serial No. 349,714

2 Claims. (Cl. 105—15)

This invention relates to railway car diaphragm constructions, and more particularly to the manner of connecting such diaphragm constructions to the car body and supporting them thereon.

In my improved construction, an inner diaphragm is provided to form the passageway leading from one car into the adjacent car, one end of this diaphragm being secured to the car body and the other being connected to an inner face plate, which is supported upon a buffer member located at the bottom of the face plate. Both the buffer member and the upper end of the face plate are connected to the car body by structures which permit them to move toward the car body and to assume angular positions with respect thereto, and also permit a limited amount of vertical movement relative to the car body. Means are provided to positively hold the face plate in the center of the car body end at all times, so that it will line up properly with the face plate of the adjacent car. Outer face plates are pivotally connected to each side of the inner face plate, and outer diaphragms extend from these face plates to the car body end to close the spaces between the cars.

Various other objects and advantages of the invention will be apparent upon reference to the following description and accompanying drawings, in which

Fig. 1 is a side elevation of the adjacent end portions of railway cars which are coupled together.

Fig. 2 is a sectional view taken on the line 2—2 of Fig. 1.

Fig. 3 is a sectional view taken on the line 3—3 of Fig. 2.

Fig. 4 is a sectional view taken on the line 4—4 of Fig. 3.

Fig. 5 is a sectional view taken on the line 5—5 of Fig. 4.

Fig. 6 is a sectional view taken on the line 6—6 of Fig. 2.

Fig. 7 is a sectional view taken on the line 7—7 of Fig. 6.

Fig. 8 is a sectional view taken on the line 8—8 of Fig. 6.

Fig. 9 is a sectional view taken on the line 9—9 of Fig. 2.

Fig. 10 is a plan view of the adjacent ends of two coupled cars showing the positions the diaphragms assume when the cars are on curved track.

Fig. 11 is a sectional view taken on the line 11—11 of Fig. 9.

Fig. 12 is a sectional view taken on the line 12—12 of Fig. 2.

Fig. 13 is a view similar to Fig. 12 but showing the position the parts assume when the cars are on curved track as shown in Fig. 10.

The reference numerals 14 and 16 indicate

adjacent railway cars which are coupled together by conventional couplers 13 and 20. Diaphragm structures designated generally by the numerals 22 and 24 are secured to the ends of the cars 14 and 16 respectively, and since these diaphragm structures are identical in construction, only one will be described.

Referring to Fig. 9, the numeral 26 designates the floor of the car body, and 28 is a vertically extending plate welded or otherwise secured thereto and forming a part of the body end sill structure. Secured to the plate 28 in spaced relation on each side of the longitudinal center line of the car by bolts 30 are brackets 32 which are U-shaped in cross-section, as shown in Fig. 11, and a wear plate 34 is welded or otherwise secured to the upper surface of the web part of the U-shaped portion of each of the brackets. Shoes 36 having wear plates 38 secured to their bottom surfaces are slidably mounted in the brackets, and are provided with portions 40 which fit between spaced ears 42 welded to a buffer angle 44, being pivotally connected to the ears by bolts 43. It will be seen from this that the buffer angle is supported on the brackets 32 but is free to move toward or away from the end sill or to move angularly with respect to same.

Each of the shoes 36 also have formed on them spaced flanges 48 between which an eye 50 having flat sides bearing against the flanges is located, and this eye is pivotally connected to the flanges by a bolt 52. The eye has a shank 54 to which is welded a piece of tubing 56, although it will be understood that the tubing and eye may be formed as an integral part if desired. The tubing extends through relatively large openings 58 and 60 formed in the bracket 32 and plate 28 respectively, and through a smaller opening 62 formed in a plate 64 which is a part of the end sill structure. A compression spring 66 surrounds the tubing and bears against a shoulder formed on the eye 50 at one end and against a washer 68 which abuts the plate 64 at the other end. A key 70 extending through slots formed in the tubing limits movement of the latter away from the end sill, and the spring 66 is so designed that it will be under some compression when the parts are in the position shown in Fig. 9. It will be seen that this arrangement permits the buffer angle to move toward the end sill when it is engaged by the buffer angle of an adjacent car as when the cars are being coupled together or are running on curved track where they assume an angular relationship to each other, the springs cushioning such movement and tending to return the buffer angles to normal position and the keys 70 preventing movement beyond that position.

Pivottally connected to the plate 28 by hinges 60 is a floor plate 74 which is held down tightly against the upper surface of the buffer angle 44

by a spring member 76, one end of which is secured to the plate 28 and the other end of which is connected to lugs 78 secured to the underside of the floor plate. This construction permits the buffer angle to slide under the floor plate but insures that the latter will be held firmly against the buffer angle at all times.

In order to properly center the buffer angle, the following construction is provided. A bar 80 having a head portion 82 pivotally connected by a bolt 84 between spaced ears 86 secured to the buffer angle 44, extends through a guide 88 secured to the plate 28 by bolts 89 and through openings 90 and 92 formed in that plate and in the plate 64 respectively. Secured to the plate 64 is a member 94 which serves to hold a sleeve 96, the latter being clamped to the member 94 by a strap 98 which is fastened to the member 94 by bolts 100. As will be seen in Figs. 6 and 8, the bar 80 extends through the sleeve, and there are two semi-cylindrical members 102, formed of alternate layers of rubber and fabric or similar material, located between the bar and the sleeve to keep them out of contact with each other and to permit a limited amount of movement of the bar relative to the sleeve, for a purpose to be presently described. The bar is of course free to slide within the members 102, such sliding movement taking place when the buffer angle is moved toward the end sill. A key 103 extending through an opening in the bar is adapted to engage the sleeve when the buffer angle has returned to normal position to prevent further outward movement of the bar within the sleeve.

As shown in Fig. 7, the opening 104 in the guide 88 is elongated in shape, being of greater height than its width, and its surfaces at either side being machined flat as at 106. At the point where it passes through the guide, the bar has wear plates 108 welded to its sides, and these wear plates bear against the flat surfaces 106 on the guide, thereby preventing any horizontal movement of the bar with respect to the guide but permitting it to move vertically a limited amount for a purpose to be described later.

Secured to the top of the buffer angle 44 by bolts 109 is the lower portion of an inner face plate 110 of U-shape, the space 112 between the legs of which constitutes a passageway between adjacent cars. As best shown in Figs. 3 and 4, the upper end of this face plate is yieldably connected to and centered with respect to the car body by the following structure. Spaced lugs 114 welded to the face plate have pivotally connected between them by a bolt 116 a trunnion 118 to which the head 119 of a tubular member 120 is pivotally connected by a bolt 122. This tubular member is slidably supported within a sleeve 124, to one end of which is welded an eye 126 which is pivotally connected by a pin 128 to lugs 129 formed on a support 130 which is secured in any suitable manner to the body end member 132. Mounted on the outside of the sleeve 124, and rigidly connected thereto by a bolt 134 which extends through slots 136 formed in the tubular member 120, is a wedge member 138 having angularly inclined surfaces 140 formed on it. Correspondingly inclined surfaces 142 are provided on the support 130, and blocks 144 of rubber or other resilient material having metal plates 146 and 148 vulcanized to them, are secured between the inclined surfaces. As shown in Fig. 4, the plates 146 abut against shoulders 150 formed on the wedge member 138, and the plates 148 abut

against shoulders 152 provided on the support 130, so that any tendency of the wedge member to move toward the support 130 will be resisted by the compression action of the rubber blocks. 5 The assemblies of the blocks 144 and plates 146 and 148 are held between the inclined surfaces on the wedge member 138 and support 130 by means of a member 149 which is secured to the support by bolts 151, there being spacers 153 interposed between the plates 148 and the member 149 to hold the wedge member out of contact with the member 149 since it moves laterally with respect thereto.

A compression spring 154, one end of which 15 bears against the head 119 of the tubular member and the other end of which bears against the wedge member, surrounds the sleeve 124 and tends to move the face plate away from the car body, this movement however being limited by 20 the engagement of the bolt 134 with the end of the slots 136 in the tubular member, the spring 154 being so proportioned that it is under some compression even when the bolt engages the end of the slot. It will be seen from the above that 25 when pressure is applied against the face plate, the latter is free to move toward the car body in a direction parallel with the longitudinal centerline thereof, the tubular member 120 sliding within the sleeve 124 and the spring 154 being 30 compressed and thereby cushioning such movement and tending to return the face plate to normal position when the pressure ceases. Any tendency of the upper end of the face plate to move sidewise with respect to the car body is 35 resiliently resisted by the compression action of the rubber blocks 144.

As shown in Fig. 12, a vertically extending I-beam 156 is secured to the body end member 132, and one end of a flexible inner diaphragm 40 158 formed of rubberized fabric or other suitable material is connected to the I-beam by fastening devices 160, the other end of the diaphragm being connected by fastening devices 162 to a member 164 which is secured to the face plate 113.

45 To improve the appearance and to protect passengers from being injured by being caught in the crack between the contacting face plates of adjacent cars, a roller curtain 166 formed of any suitable flexible material has its ends secured in 50 housings 168, one of the housings being located in one car while the housing to which the opposite end of the curtain is attached is located in the adjacent car. The housings are supported on members 170 which in turn are secured to the 55 I-beams 156. One end of the curtain is wound on a spring roller 172 which keeps the curtain taut at all times. It will be understood of course that there is a similar curtain on the other side of the passageway 112.

60 Since in streamlined trains it is important that the spaces between adjacent cars be closed or covered to maintain smooth unbroken surfaces at the sides and top of the cars, outer diaphragms 174, formed of any suitable flexible material, are 65 provided at each side of each car. These outer diaphragms are secured at one end to the car body member 176 by fastening devices 178. The other end of each diaphragm is connected by fastening devices 180 to channels 182 which are 70 secured to outer face plates 184, which as shown in Fig. 2 have portions 186 at their upper ends which are curved to conform to the shape of the top of the car, such portions terminating substantially in line with the outer side edges of the 75 inner face plate 110. The lower portions 188 of

the outer face plates are in line with the face of the buffer angle 44. The outer face plates are supported from and pivotally connected to the inner face plate 118 by hinges 189.

Secured to the inner face plate are brackets 190, and a block 192, provided with trunnions 194 which are received in bearing portions 195 formed in the brackets, is pivotally supported in each of these brackets. A threaded bolt 196 having an eye 198 formed at one end, which eye is secured by a bolt 200 between spaced lugs 202 welded to the portions 186 and 188 of the outer face plate, extends through a hole formed in the block 192 and is slidably therein. A compression spring 204 bears against the block at one end and at the other end engages washers 206 backed up by nuts 208 threaded on the bolt, the nuts providing an adjustment whereby the compression of the spring may be varied. At the other end of the bolt, nuts 210 are threaded thereon to limit sliding movement of the bolt in the block in the one direction. The nuts 210 may be adjusted to vary the length of travel of the bolt 196 in the block 192. As shown in Fig. 12, the nuts 210 are adjusted to such position that they will engage the block 192 when the outer face plate is parallel to the end of the car body, and will prevent any further outward movement of the outer face plate.

When the cars are operating on curved track, the various parts of the structure take the positions shown in Fig. 10, the spring 66 of the buffer angle toward the inner side of the curve being compressed to permit the buffer angle to lie at an angle with respect to the end of the car body, instead of extending parallel thereto as it normally does. This results in the buffer angles and inner face plates remaining in contact with each other while the cars are rounding the curve. The outer diaphragms 174 on each car at the inner side of the curve will be compressed, and the outer face plates at that side will also remain in contact with each other, whereas at the outer side of the curve the outer diaphragms will be expanded to a straight position, and the outer face plates at that side will be separated from each other, as shown in Fig. 10. In Fig. 13, it will be seen that the compression springs 204 will resiliently resist movement of the outer face plates toward the car body, while the engagement of the nuts 210 with the blocks 192 will prevent movement of the outer face plates beyond a position where they will be parallel to the end of the car body and in line with the inner face plate.

As shown in Fig. 11, since the shoes 36 which support the buffer angle merely rest in the U-shaped brackets 32, they are free to move upwardly a limited amount, as indicated by the reference character X, to permit the buffer angle and the parts supported thereon to tilt slightly. As shown in Fig. 9, the openings 60 and 58 in the plate 28 and bracket 32 respectively, are made sufficiently larger than the diameter of the spring so that the latter will not contact these members during this tilting movement. Provision for this tilting movement is necessitated because of the fact that during certain operating conditions, the platform of one car may extend at a slight angle with respect to that of the adjacent car. As described above, the opening 104 in the guide 88 is elongated in shape to permit vertical movement of the bar 80 in the guide, the wear plates 108 bearing against the flat surfaces 106 of the opening 104 to center the buffer angle and associated parts and to prevent sidewise movement

of them. At the top of the structure, there is a sufficient amount of clearance provided at the points where the eye 126 fits between the lugs 129 and where the pin 128 passes through the opening in the eye 126 to permit the opposite end of the tube 120 and sleeve 124 to move upwardly during such tilting movement of the face plate and buffer angle.

It will be seen from the above that I have provided a construction in which the various parts are supported in such manner that they will normally be held in position where they will line up properly with and be in contact with the corresponding parts of an adjacent car, but will be free to move to different positions when necessitated by changes in the relationship of the two coupled cars during operation, the parts however being held in proper centered position at all times to insure that the passageways in the ends of adjacent cars will always line up with each other.

While the invention is susceptible of various modifications and alternative constructions, I have shown in the drawings and have described in detail the preferred embodiment, but it is to be understood that I do not thereby intend to limit the invention to the specific form disclosed, but intend to cover all modifications and alternative constructions falling within the spirit and scope of the invention as defined in the following claims.

I claim:

1. In combination with a rail car body, a face plate, members located at the bottom thereof to support said plate, said members allowing movement of the face plate toward the car body, a tube connected to the upper end of the face plate, a sleeve in which said tube is slidably received, a wedge-shaped member mounted on and rigidly connected to the sleeve, said wedge-shaped member having angularly inclined surfaces formed thereon, a support secured to the car body and having angularly inclined surfaces formed on it, blocks of resilient material secured between the angularly inclined surfaces on the wedge-shaped member and the support, and a spring mounted on the tube between a shoulder formed thereon and said wedge-shaped member, said spring being compressed when said face plate moves toward the car body, and said blocks of resilient material serving to resist lateral movement of said face plate relative to the car body.

2. In combination with a rail car body, a face plate spaced from the car body, means located at the bottom thereof to support said plate, said means allowing movement of said face plate toward the car body, a member connected to the upper end of the face plate and extending toward the car body, a support secured to the car body, a sleeve pivotally connected to the support, said member being slidably mounted in said sleeve, a compression spring located on the outside of said sleeve and serving to resist movement of the upper end of the face plate toward the car body, a wedge-shaped member having inclined surfaces formed on it secured to said sleeve, said sleeve having correspondingly shaped inclined surfaces formed on it, and pieces of resilient material interposed between the inclined surfaces on the wedge-shaped member and on the support, said resilient material serving to yieldingly resist lateral movement of the upper end of the face plate relative to the support.

MARTIN P. BLOMBERG.
